UNITED STATES PATENT OFFICE.

LUDWIG ZWENG, OF PFRONTEN-STEINACH, GERMANY.

FOLDING DRAWING PEN.

1,425,738.

Specification of Letters Patent. Patented Aug. 15, 1922.

Application filed May 28, 1920. Serial No. 385,009.

(GRANTED UNDER THE PROVISIONS OF THE ACT OF MARCH 3, 1921, 41 STAT. L., 1313.)

To all whom it may concern:

Be it known that I, LUDWIG ZWENG, a citizen of the German Republic, and resident of Pfronten-Steinach, Bavaria, Germany, have invented certain new and useful Improvements in Folding Drawing Pens, (for which I have filed application for patent in Germany, under date of December 20, 1918, Patent No. 320,545), of which the following is a specification.

My present invention relates to a folding drawing-pen on which the movable pen-blade is held in an uplifted position as well as in such ready for use by means of a spring, as are already known.

The new characteristic feature of my invention consists therein that an elastic tongue is produced by means of a slitting on the rigid pen-blade so that a special spring is thereby dispensed with.

The accompanying drawing shows my invention in side-view.

The movable lever *a* of said drawing pen

is movably i. e. upliftably lodged in the well-known manner at *b* on the rigid lever *c*. Below the pivot *b* is the elastic tongue *f* produced by the slitting of the rigid lever *c* which tongue abuts against the nose *e* of the movable lever *a* holding it rigid.

Having now described my invention what I claim as new and desire to secure by Letters Patent is:—

A drawing pen having a fixed blade provided at its inner end, on its outer side with a spring tongue, and a pivoted blade the inner end of which has edges arranged at an angle to each other and also arranged to bear on said spring tongue to hold said pivoted blade in either open or closed position.

In testimony whereof I have hereunto signed my name this 6th day of March 1920, in the presence of two subscribing witnesses.

LUDWIG ZWENG.

Witnesses:

PAUL DREY,
MARIANNE FLUMANN.
